ATTORNEY.

UNITED STATES PATENT OFFICE

2,386,460

FRUIT JAR HOLDER AND LID TIGHTENER

Rudolph F. Heim, St. Joseph, Mo.

Application September 18, 1943, Serial No. 502,981

5 Claims.

(Cl. 81—3.44)

My invention relates to certain new and useful means for securely holding a fruit jar while tightening the caps, and means to grip the caps while the tightening forces are being applied.

Primarily the invention has for its object to provide a device that can be made from certain kinds of hard wood which are not used in defense work. Another object is to provide such a device which when made of wood can be shaped with machines that are at present probably idle, as for example jig-saw machines.

Another object is to provide, as one unit, a jar holder that can be removably secured to a table or similar support and held in its jar-gripping position by leg pressure, thereby leaving the user's hands free to manipulate a jar cover or cap turning clamp unit.

A still further object is to provide apparatus for use in household canning operations to tighten the covers or caps on jars, which apparatus is non-corroding, can be readily taken apart for cleaning, and can be used on jars of different shapes.

Another object is to provide apparatus of the kind heretofore mentioned that can be made of plastic, hard rubber (natural or synthetic), or any other suitable material, by die stamping, molding or other known methods.

Other objects will in part be obvious and in part pointed out hereinafter.

To the attainment of the aforesaid objects and ends the invention still further resides in the novel details of construction, combination and arrangement of parts, all of which will be first described in the following detailed description, and then be particularly pointed out in the appended claims, reference being had to the accompanying drawing, in which:

Fig. 1 is an isometric perspective view of my invention in use.

Fig. 2 is a plan view of the jar clamp open, parts being broken away.

Fig. 3 is a plan view of the cap or cover clamp open, parts being removed.

Fig. 4 is an end view, looking in the direction of the arrow in Fig. 1.

In the drawing in which like letters and numerals of reference indicate like parts in all the figures, 1 and 2 indicate the two parts of the jar clamp unit, detachably connected by a pivot connection consisting of a cylindrical socket 3^a in the member 2 and a cylindrical projection 3 on the member 1, which fits the socket.

When the device is made from one piece of wood, the socket 3^a is lined with a thin strip of

veneer 13 to fill the void left by the saw around the pivot projection 3. This veneer not only gives the hinge a smooth action but also reinforces the cross-grain of the wood.

The member 2 has a pin receiving slot 15 to receive a pin 4 on the pivot-projection 3 when the parts 1 and 2 are held together, and thus prevent the hinge joint separating. However when the parts 1 and 2 are opened apart to their fullest extent (limited by contact of the end 1^a with the shoulder 2^a) the hinge joint can be disconnected.

The jaw parts 1 and 2 have complementary recesses 5 and 6 formed and shaped to receive jars that are either round or square and of the larger or smaller sizes (see Fig. 2). The recesses 5 and 6 are preferably lined with felt or other friction strip material 14 to hold the jars firmly in place when body pressure is applied against handle-lever 10 (see Fig. 1).

The jar clamp may be, and preferably is, fastened to a table 7 or other suitable support by means of an angle piece 12 carrying a clamp screw 8 and having dowel holes to receive dowel pins 11 (Figs. 2 and 4). The angle piece 12, operating through the dowels 11 and screws 8 serves, to clamp the part 2 firmly to the support 7. Since the handle-lever 10 projects beyond the table edge it may be pressed towards the handle 9 to close the clamp firmly about the jar J by pressure of one's leg L.

The lid clamp is of substantially the same construction as the jar clamp save that it need have but one hold 20 and short handles 25. The pivot member 21 and liner 17 are of the same construction as the pivot member 3 and liner 13. Preferably there is provided a slight hump or projection at 24 which prevents the members 16, 25 and 18, 25 contacting unless sprung together by squeezing the handles 25 together, thus obtaining a spring action between the parts so that these slightly open when pressure is released to allow the jaws to disengage the lid.

The lid clamp 16, 18 may be operated by one hand as indicated in Fig. 1, or, by placing the left hand over the hinge and grasping the handles 25 with the right hand, the device may be turned by both hands.

As shown in Fig. 3 the pivot member 21 of the hinge has a pin 22 while the member 16 has a slot 23 to receive the pin to prevent separation of the jaw members 16, 18 when the device is in use but permitting them to be separated when in the fully open position shown in Fig. 3, by

lifting the member 21 along its axis out of the socket.

The jar clamp unit 1 and 2 may be operated on the left side of table 7, as shown in Fig. 1, or said jar clamp may be turned upside down and operated on the reverse side by being fastened to the right side of table 7.

The dowel pins 11 are spaced in such a position on part 2 that they will fit into the dowel holes of part 12 from either end.

From the foregoing description, taken in connection with the accompanying drawing, it is thought the construction, operation and advantages of my invention will be clear to those skilled in the art, and I desire it understood that changes in the design, form and details of construction may be made within the scope of the claims appended hereto, without departure from the invention.

What I claim is:

1. A clamp comprising two wooden bodies having adjacent straight edges and each having one-half an article receiving opening, one of said bodies adjacent one end having a generally cylindrical opening through the same and a passage from said opening through the aforesaid straight edge of that body, the other body having a laterally projected generally cylindrical pivot to fit within said generally cylindrical opening and said passage and constitute therewith a hinge joint, means to limit the opening movement of the clamp, and a pin and slot connection between the elements of the hinge joint preventing their separation save when the clamp is fully open, said two clamp members each having a handle.
2. A clamp comprising two wooden bodies having adjacent straight edges and each having one-half an article receiving opening, one of said bodies adjacent one end having a generally cylindrical opening through the same and a passage from said opening through the aforesaid straight edge of that body, the other body having a lat-

erally projected generally cylindrical pivot to fit within said generally cylindrical opening and said passage and constitute therewith a hinge joint, means to limit the opening movement of the clamp, and a pin and slot connection between the elements of the hinge joint preventing their separation save when the clamp is fully open, said two clamp members each having a handle, and means to effect a slight opening of the clamp when clamping pressure is released from the handles.

3. In a clamp composed of two clamp levers, the improvement which includes a cylindrical socket in one lever and a cylindrical member on the other lever and adapted to fit within said socket and therewith constitute the pivotal fulcrum for the levers, one of said levers at the pivotal fulcrum having a slot and the other lever having a pin disposed to enter said slot while the clamp is in use and to leave said slot when the levers are separated a predetermined distance, said clamp levers having between them at least one article-receiving opening.

4. The clamp of claim 3 wherein there is provided a suitable liner in said socket for purposes described.

5. A clamp comprising two wooden bodies having adjacent straight edges and each having one-half an article receiving opening, one of said bodies having adjacent one end a generally cylindrical opening through the same and a passage from said opening through the aforesaid straight edge of that body, the other body having a laterally projected generally cylindrical pivot to fit within said generally cylindrical opening and said passage and constituting therewith a hinge joint, means to limit the opening movement of the clamp, and a connection-maintaining means between the elements of the clamp members to prevent their being separable along the axis of the hinge joint save when the clamp is fully open, said two clamp members having a handle.

RUDOLPH F. HEIM.
